UNITED STATES PATENT OFFICE.

JOSEPH N. LE VASSEUR-BELISLE, OF WORCESTER, MASSACHUSETTS.

GUIDE-EYE FOR LOOM-SHUTTLES.

1,066,824.

Specification of Letters Patent.

Patented July 8, 1913.

Application filed April 3, 1912. Serial No. 688,135.

To all whom it may concern:

Be it known that I, JOSEPH N. LE VASSEUR-BELISLE, a citizen of the United States of America, residing at 65 Southgate street, 5 Worcester, in the county of Worcester and State of Massachusetts, have invented certain new and useful Improvements in Guide-Eyes for Loom-Shuttles, of which the following is a specification.

10 This invention relates to weaving shuttles and particularly to guide eyes for shuttle threaders.

An object of this invention is to provide a guide eye of the character noted which 15 will be held in the holder by friction, thus obviating the provision of screw threads or other fastening devices for retaining the same in place.

A still further object of this invention is 20 to provide a channel member comprising a substantially cylindrical portion, tapered toward one end and provided with an apertured flange to receive thread adapted to extend through the cylindrical member, the 25 said flange being preferably formed integral with the cylindrical member and constituting a unitary structure capable of being applied to and removed from the shuttle and being capable also of retaining its place in 30 the shuttle by frictional contact of the member and the shuttle.

With the foregoing and other objects in view, the invention consists in the details of construction and in the arrangement and 35 combination of parts to be hereinafter more fully set forth and claimed.

In describing the invention in detail, reference will be had to the accompanying drawings forming part of this specification, 40 wherein like characters denote corresponding parts in the several views, and in which—

Figure 1 illustrates a perspective view of a fragment of a shuttle, the same being 45 broken away showing a threader embodying the invention applied thereto; Fig. 2 illustrates a transverse sectional view of the shuttle and threader; Fig. 3 illustrates a perspective view of the threader; Fig. 4 50 illustrates a longitudinal sectional view of the said threader, the same being taken on the line B—B of Fig. 5; and Fig. 5 illustrates a sectional view on a line corresponding 55 with the line A—A of Fig. 4.

In these drawings 6 denotes the shuttle which may be of any appropriate construc-

tion having the shuttle threader applied thereto, the said shuttle threader comprising a substantially cylindrical body 7 tapered to form a nose 8 at one end and having an integral flange 9 preferably formed by doubling the metal on itself as shown at 60 10. The flange 9 is provided preferably with a longitudinally disposed aperture 11 adapted to receive the thread 12 in passing 65 the same through the threader.

In forming the body 7, the same is slit longitudinally from one end to a point intermediate the other end thereof as shown at 12' which is for the purpose of producing 70 a springing action of the said body in order that it may bind in the bore 13 of the shuttle which is designed to receive it, it being understood that the inventor relies on frictional contact of the said cylindrical member 75 with the wall of the bore 13 for effecting an anchorage or retention of the shuttle threader within the shuttle.

In Fig. 2, there is illustrated a spirally wound wire or other member 14 of such 80 flexibility as to permit its insertion in the shuttle threader and through the aperture or eye 11 of the flange thereof for the purpose of engaging the thread whereby the said 85 thread may be drawn therethrough.

In the formation of the flange 9, it will be observed that it is integral with the material of which the cylindrical portion 7 is formed and that the said flange 9 is relatively long and that it is doubled on itself, as stated, 90 and overlies the top portion of the member 7, and is preferably fitted into an aperture in the upper portion of the cylindrical member, the joint or edge of which is shown at 95 15, the said portion of the flange which is bent back to overlie the cylindrical member 7 being indicated by the numeral 16. As the flange and the cylindrical member are preferably formed of resilient material, the portion 16 may serve as a friction member 100 or element for bearing against the wall of the bore of the shuttle for the purpose of retaining the shuttle threader in place and as the construction of the device permits its being stamped from sheet metal, it will be 105 observed that the same can be manufactured at comparatively small cost and that it will prove durable and efficient in use.

I claim—

1. In a shuttle threader, a substantially 110 cylindrical body having a tapered nose and a flange extending from the end of said nose

- rearwardly of said cylindrical body, the said cylindrical body having a portion of its top portion removed and having the flange lying in the opening formed by the removal 5 of said portion of the cylindrical body, the said flanged portion having an eye formed therein communicating with the interior of the cylindrical body and a shuttle to which the threadder is applied.
- 10 2. A shuttle threadder comprising a substantially cylindrical body and having a longitudinally disposed slit, and an opening in its top portion, a flange extending from one end of the cylindrical body and having 15 a portion thereof extending over the apertured portion of the cylindrical body and

lying in the said aperture, and the said flanged portion having an opening communicating with the interior of the body.

3. In a shuttle threadder, a substantially 20 cylindrical body, laterally expansible, and a flange extending from the said body and extending rearwardly over the said body and having an aperture in communication with the interior of the body. 25

In testimony whereof, I affix my signature in the presence of two witnesses.

J. N. LE VASSEUR-BELISLE.
